UNITED STATES PATENT OFFICE.

MARK J. MASTERS, OF BROOKLYN, NEW YORK.

DESIGN FOR A SIGN-LETTER.

SPECIFICATION forming part of Design No. 22,325, dated April 4, 1893.

Application filed March 8, 1892. Serial No. 424,226. Term of patent 3½ years.

To all whom it may concern:

Be it known that I, MARK J. MASTERS, a subject of the Queen of Great Britain, residing in Brooklyn, county of Kings, and State of New York, have invented and produced a new and original Design for Sign Letters and Figures, of which the following is a specification.

In the accompanying drawings: Figure 1 is a face view of a letter made in accordance with my design; and Fig. 2 is a transverse section through the sign and letter showing the formation of the surface of the letter.

The leading feature of my design consists of a letter or figure having the general appearance of a setting of cut jewels or precious stones; that is to say, the straight or curved lines imparting the form to the figure or letter have the appearance of cut jewels or precious stones placed in straight or curved rows.

On reference to the drawings, A represents the entire letter. The lines are formed into a series of groups *a* of inclined planes or facets *a'*, the groups all being alike and following each other in the line. The planes *a'* of each group are triangular in shape and with their apexes together in the center, thus making the group square in shape. 25

Having thus described my invention, I claim— 30

The design for sign letters herein described and illustrated in the accompanying drawings.

In witness whereof I have hereunto signed my name in the presence of two subscribing 35 witnesses.

MARK J. MASTERS.
